C. H. UPRIGHT

GAS BURNER

Filed May 14, 1926

INVENTOR
CHARLES H. UPRIGHT.

BY *Johnston Langlois*
ATTY.

UNITED STATES PATENT OFFICE.

CHARLES HENRY UPRIGHT, OF EDMONTON, ALBERTA, CANADA.

GAS BURNER.

Application filed May 14, 1926. Serial No. 109,118.

This invention relates to improvements in gas burners and the objects of the invention are to provide a simply constructed and efficiently operable adjustable burner provided with adjustable means for regulating the extent of the illumination and the amount of gas consumed.

Further objects are to provide an improved gas burner of economical construction with which more satisfactory results will be obtained with a minimum consumption of fuel.

With these and other objects in view, the invention consists essentially in the combination, with a gas burner provided with engaging means, of an adjustably mounted cover adapted to engage with and fit over the burner.

Referring now to the drawings in which like characters of reference indicate corresponding parts in each figure:

Figure 1 is a perspective view of my improved gas burner, and

Figure 2 is a longitudinal, sectional, view.

Referring more particularly to the drawings, in which a preferred example of my invention is disclosed, 10 designates the gas supply pipe communicating with a gas pipe 12 provided with an air intake 13 of any suitable construction, here shown as a sleeve 14 having openings 15 therein adapted to register with openings 16 in the gas pipe. On the other end of the pipe 12 is a vertical gas pipe 17 on the open end of which is mounted a funnel member 18 provided with a spider 19 in which is a screw threaded

opening 20. This opening is designed to engage with the threaded stem 21 of a supporting pin on which, through a threaded opening in the apex thereof 23, is mounted a cone-shaped cover member 24 adapted, 40 on being rotated, to move upwardly or downwardly in relation to the funnel 18.

In operation it will be seen that, by turning the threaded stem 21, the cover 24 will be moved upwardly or downwardly in its 45 relationship to the funnel 18, thereby regulating the extent of the flame in the funnel member and, at the same time, spreading it.

As many changes could be made in the above construction and many apparently 50 widely different embodiments of my invention, within the scope of the claim, constructed without departing from the spirit or scope thereof, it is intended that all matter contained in the present specification and 55 accompanying drawings be interpreted in an illustrative and not in a limiting sense.

What I claim as my invention is:

A gas burner comprising in combination with a gas supply pipe, a funnel for said 60 pipe, a spider formed in the funnel having a threaded opening therein, a pin formed with a head and adapted to adjustably engage with the spider, and a substantially cone shaped cover member rigidly mounted 65 on said pin.

In witness whereof I have hereunto set my hand.

CHARLES HENRY UPRIGHT.
